UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A FRAME FOR TABLES, &c.

SPECIFICATION forming part of Design No. 23,422, dated July 3, 1894.

Application filed May 21, 1894. Serial No. 512,012. Term of patent 3½ years.

To all whom it may concern:

Be it known that I, LOTHAR VON GRAVE, a subject of the Emperor of Germany, residing at Wallingford, New Haven county, State of Connecticut, have invented and produced a new and original Design for Frames for Tables, &c., of which the following is a description, reference being had to the accompanying drawings, which form a part of the same, and

wherein—

Figure 1 is a perspective view of a table illustrating frames embodying by design applied thereto. Fig. 2 is a plan view of the shelf of the table illustrating my design, said shelf being shown detached and one-half only of which is shown in full lines. Fig. 3 is a plan view of the table-top illustrating my design, said top being shown detached and one-half only of which is shown in full lines.

The essential characteristics of my design consist of an inner beaded or ornamental rim and an openwork leaf-like border surround-

ing said inner beaded or ornamental rim and following the contour thereof.

In the drawings *a* represents the table-top embodying my design, the inner beaded or ornamental rim being indicated by the letter *b*. This inner beaded or ornamental rim is surrounded by an openwork, leaf-like border *c*, which follows the contour thereof. A shelf *d* shown extending between the table-legs *e* of the table, likewise embodies my design, and is similar in every respect to the top *a*, the letter *f* indicating the inner ornamental rim which is surrounded by an openwork, leaf-like border *g* similar to the border *c* of the table-top.

What I claim is—

The design for frames for tables &c. substantially as shown and described.

LOTHAR VON GRAVE.
